[57] CLAIM

The ornamental design for a combined abrasive dental
instrument and cap for removing discolorations on
teeth, as shown and described.

DESCRIPTION

FIG. 1 is an exploded top perspective view of a com-
bined abrasive dental instrument and cap for removing
discolorations on teeth showing my new design;

FIG. 2 is an exploded left side elevational view thereof;

FIG. 3 is a right side elevational view thereof;

FIG. 4 is a rear elevational view thereof;

FIG. 5 is a front elevational view thereof;

FIG. 6 is a top plan view thereof; and

FIG. 7 is a bottom plan view thereof.
